UNITED STATES PATENT OFFICE.

FRANK S. BISSELL, OF STERRETT, ALLEGHENY COUNTY, PENNSYLVANIA.

GRATE.

SPECIFICATION forming part of Letters Patent No. 351,155, dated October 19, 1886.

Application filed September 25, 1885. Serial No. 178,111. (No model.)

To all whom it may concern:

Be it known that I, FRANK S. BISSELL, of Sterrett, in the county of Allegheny and State of Pennsylvania, have invented a new and useful Improvement in Grates; and I do hereby declare the following to be a full, clear, and exact description thereof, reference being had to the accompanying drawings, forming a part of this specification, in which--

10 Figure 1 is a plan view of my improved grate. Fig. 2 is a similar view of the same when the grate-bars are tilted to dump the contents of the grate. Fig. 2^a is a perspective view of a part of one of the grate-bars and of the bar for tilting it. Fig. 3 is a front elevation of the grate, as shown in Fig. 1. Fig. 4 is a vertical cross section of the grate on the line *xx* of Figs. 1, 2, and 3. Fig. 5 is a perspective plan view, partly in section, of the 20 grate-bars and of the mechanism for reciprocating and tilting them. Fig. 6 is a plan view of a locking device which I employ for locking the tilting mechanism.

Like symbols of reference indicate like parts 25 wherever they occur.

My invention relates especially to grates for open fire-places, open fire-place heaters, or open fire-place stoves, but is generally applicable to cook-stoves, ranges, and other like 30 places, where a light agitating and dumping grate is desirable.

It has for its object to obtain a dumping-grate of that class wherein the fuel is agitated by a sliding or reciprocating motion of the 35 bars, and is an improvement upon the device shown and claimed by me in Letters Patent No. 238,636, dated the 8th day of March, 1881.

I will now proceed to describe my invention more specifically, so that others skilled in the 40 art to which it appertains may apply the same.

In the drawings, 2 indicates the main or fixed frame supporting the grate, which will of course vary, according to the class of grates to which the invention is applied.

45 4 4^a represent sliding frames, which are mounted upon and supported by the main frame 2. In the drawings they are two in number, arranged side by side, each consisting of a hollow rectangular metal frame or casting. The 50 grate-bars proper, 5, are fixed within secondary frames 6, also preferably of a hollow ob-

long form, and provided at their ends with trunnions 7, which fit within bearings on or in the body of the frames 4 4^a. The frames 6 are made of proper size, and one is pivoted within 55 each of the sliding frames, so as to be capable of oscillations therein.

8 is the agitating-bar or crank-shaft, which has bearings on the fixed frame 2, and extends from one side of it to the other, transversely 60 to the sliding frames 4 4^a and underneath them. One of the sliding frames, 4, is provided with a downwardly-projecting forked lug, 9, which straddles an eccentrically-situate crank on the shaft 8, and the other sliding frame, 4^a, is connected with the shaft by an eccentric lug, 10, affixed to the latter and fitting within a notch or fork on the bottom of the frame. Owing to the construction specified—viz., the 65 sliding frames having their bearings one above and one below the center of motion of the agitating-shaft, reciprocating rotation of the latter will cause the frames to slide backward and forward, thus effecting a thorough agitation of the fuel, which is superimposed 70 thereon. The shaft 8 projects beyond the front of the grate, and is operated by a lever-handle, whose end is inserted into a polygonal socket, 11, in the projecting shaft, Fig. 5.

The grate is tilted by the following mechanism. (See Figs. 4 and 2^a.) Each of the pivoted frames 6 has a downwardly-projecting arm or finger, 12, which is affixed to the bottom of its frame at the end thereof. These arms pass through somewhat elongated holes or slots 13 85 in a sliding bar, 14, which latter extends from beyond the front of the grate underneath the sliding frames 4 4^a, transversely thereto, and is supported by brackets 15 and 16, through which the bar may be moved in a right line backward and forward. If the bar be drawn forward into the position shown in Fig. 4, the effect will be to move the lever-arms 12 and to tilt the pivoted frames upon their axes within the sliding frames 4, thereby causing the body 90 of the superposed fuel or ashes to fall into the ash box or pit beneath the grate. Pushing the tilting-bar 14 back into the position shown by dotted lines in Fig. 4 will restore the lever-arms 12 and the pivoted frames into their normal 95 positions.

It is evident that as the sliding frames 4 4^a

and their contained frames 6 are reciprocated by the shaft 8 the tilting-bar 14 will also be oscillated. This is permitted by slotting the brackets 15 and 16 longitudinally, as shown in Figs. 3 and 4. To prevent such oscillation from jarring the tilting-bar forward, and thus automatically upsetting the grate-frames, I provide the upper surface of the bar with a stud or boss, 17, and pivot to the front bar of the fixed grate-frame 2 a latch, 18, which may be moved up or down on its pivot, so as to rest upon or be separated from the tilting-bar. The stud and tilting-bar are relatively situate, so that when the latter is pushed back, as shown in Fig. 5, the latch when dropped may rest upon the bar just forward of the stud, and may thus prevent the bar from being pulled forward without raising the latch. To operate this locking device, it is best to employ the arrangement shown in Figs. 3, 5, and 6, in which the free end of the latch is provided with a curved yoke, 19, within which is set an eccentrically-pivoted cam, 20, the axis of which traverses an upright slot, 21, in the latch and enters the face of the fixed grate-frame. By turning the cam 20 upon its axis its bearing within the yoke 19 will move the latch up or down to release or engage the stud 17, as desired, and will hold it with necessary safety in the position in which it may be left. The cam may be turned by a thumb-piece, 22, of ornamental design.

The construction being substantially as specified, the fuel upon the grate may be thoroughly agitated from the front for the removal of dust by means of the agitating-shaft 8, which, upon being oscillated, will impart a horizontal sliding or reciprocating motion to the grate-bars, and at any time the contents of the grate may be dumped by drawing the bar 14 and tilting the independent pivoted frames 6. The grate bars and frames are preferably held in place by means of covering-bars 23, which are secured to the fixed grate-frame 2 and extend over and across the ends of the sliding frames 4 and over the trunnions of the pivoted frames 6.

The advantage of my improved grate over the patented grate before mentioned is that the sectional tilting arrangement of its bottom enables it not only to dump the fuel and ashes, but to clear itself immediately of them. This cannot be done where the whole bottom tilts on a single pivot, unless the ash box or pit be made quite deep. Its advantages over other grates are that I am enabled to obtain all the

advantages of the reciprocating or sliding bar grates for open fire-places, stoves, ranges, &c., of that class operated from the front without sacrificing any of the advantages pertaining to dumping-grates.

When my improved grate is used, if it should become partially filled with slate or clinkers, these can be readily removed without dumping the entire contents by drawing the tilting-bar 14 out far enough to partially upset the pivoted frames and to leave a space of sufficient area between their lateral edges and the sides of the sliding frames, and then shaking the grate, either by oscillating the shaft 8 or by vibrating the tilting-bar.

I do not desire to limit myself to the use of two tilting or two sliding frames, since a greater number of each may be employed, and, if desired, more than one tilting frame may be pivoted within each sliding frame.

What I claim as my invention, and desire to secure by Letters Patent, is—

1. The combination, in a grate, of several reciprocating frames, a crank-shaft connected with said frames, and frames carrying grate-bars pivotally mounted within said reciprocating frames, substantially as and for the purpose set forth.

2. The combination, in a grate, of several reciprocating frames, a crank-shaft connected with said frames, frames carrying grate-bars pivotally mounted within said reciprocating frames, and a movable tilting-bar extending transversely to the said tilting frames and connected therewith, substantially as and for the purpose specified.

3. The combination, in a grate, of several reciprocating frames, a crank-shaft connected with said frame, frames carrying grate-bars pivotally mounted within said reciprocating frame, a movable tilting-bar extending transversely to said tilting frame and connected therewith, and a movable lever-latch engaging with the tilting-bar, substantially as and for the purpose specified.

4. The combination of a tilting grate or bottom, a tilting-bar, a movable lever-latch engaging with the tilting-bar, and a cam, 20, bearing against a yoke on said latch, substantially as and for the purpose specified.

In testimony whereof I have hereunto set my hand this 3d day of September, A. D. 1885.

FRANK S. BISSELL.
